UNITED STATES PATENT OFFICE.

GEORGE P. FITZSIMMONS, OF NEWARK, NEW JERSEY.

PAINT-MIXING DEVICE.

1,168,618.

Specification of Letters Patent. Patented Jan. 18, 1916.

Application filed December 15, 1914. Serial No. 877,295.

To all whom it may concern:

Be it known that I, GEORGE P. FITZSIMMONS, a citizen of the United States, residing at Newark, in the county of Essex and State of New Jersey, have invented certain new and useful Improvements in Paint-Mixing Devices; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention has reference, generally, to improvements in receptacles or containers; and the invention relates, more particularly, to a novel construction of paint-can adapted for marketing ready-mixed paint.

The invention has for its principal object to provide a container or can for paint ready prepared for use having internally arranged means constructed to enable the user of the paint to thoroughly mix the same, and to loosen and stir up or mix through the paint the sediment or ingredients thereof which have settled in and even hardened in the bottom of the container or can as a result of the long standing of the same on the shelves of the dealer.

The invention has for a further object to provide a mixing means or element in combination with the commercial paint-can or container, which is simple and cheap in construction adding little to the cost of the can, and which is peculiarly efficient in construction and operation for the purpose of both loosening the settled and hardened paint ingredients in the bottom of the can and then thoroughly mixing said ingredients with the liquid content of the can.

Other objects of the present invention, not at this time more particularly enumerated, will be clearly understood from the following detailed description of the said invention.

The present invention consists, primarily, in the novel construction of combined commercial paint can and mixing element therefor hereinafter more fully set forth; and, furthermore, this invention consists in the various arrangements and combinations of the several parts thereof as well as in the

details of the construction of the same, all of which will be more fully described in the following specification and then finally embodied in the claims which are appended to and which form an essential part of this specification.

The invention is clearly illustrated in the accompanying drawings, in which:—

Figure 1 is a side elevation of the novel construction of paint-can made according to and embodying the principles of my present invention. Fig. 2 is a top view of the same. Fig. 3 is a longitudinal vertical section of the same; and Fig. 4 is another longitudinal vertical section taken at right angles thereto as indicated by the section line 4—4 in said Fig. 3, in said Fig. 4 however, the can is shown opened to permit the application of a crank-handle to the mixing element of the can.

Similar characters of reference are employed in all of the hereinabove described views to indicate corresponding parts.

Referring now to the said drawings, the reference character 1 indicates any usual form of can-body, the upper end of which is closed by a cover-member 2, secured to the can-body 1 in any suitable manner. When desired the can-body 1 may be equipped with the ordinary carrying bail 3 connected therewith in any of the usual or suitable ways.

Centrally disposed within the interior of the can-body, and upon the bottom 4 thereof, is a bearing-thimble 5 provided with the bearing opening or perforation 6. Also secured within the interior of the can-body, in any suitable manner, and spaced slightly below the upper marginal edge of the can-body, is a diametrically extending cross-bar 95 or brace 7 provided with the bearing opening or perforation 8.

The reference character 9 indicates a vertical rotatable yoke-member provided throughout its length with the elongated transverse opening 10. Connected with the lower end of said yoke-member is a journal-pin or portion 11 which is journaled in the bearing opening or perforation 6 of said bearing-thimble 5. Extending upwardly from the upper end of said yoke-member 9 is a spindle-member 12 which is journaled in said bearing opening or perforation 8 of said cross-bar or brace 7. The upper or free end of said spindle-member 12 projects

through an opening 13 provided in said cover-member 2 so as to be exteriorly disposed or projected above said cover-member. Arranged upon said spindle-member 5 is a washer 14, of any suitable resilient or flexible material, such for example as rubber, leather, fiber, etc. A compression spring-member 15 surrounding said spindle-member, and disposed between said cross-bar or brace 7 and said washer 14 forces the latter in close contact with the under side of said cover-member 2 so as to extend over and close said opening 13 against the flowing or passing of any of the fluid contents 10 of the can-body there-through should the latter be displaced from its normal upright position. An additional precaution against such leakage is provided by a second washer 16 arranged upon said spindle-member and 15 pressed downward in contact with the upper or outer surface of said cover-member 2 so as to extend over the opening 13 thereof. Secured upon the upper surface of said cover-member 2 is an upstanding circular flange or collar 17 adapted to surround and inclose the outwardly projecting end of said spindle-member 12. Said flange or collar 17 is provided with a closing member or cap 18, which closes over the space inclosed by 20 said flange or collar. This closing member or cap 18 may be secured in place by solder, or any desirable form of mechanical means, and is adapted to be cut away or otherwise removed when access to said upwardly projecting end of said spindle-member 12 is desired, for purposes to be subsequently described. Said free upper end of said spindle-member 12 is preferably provided with a squared or rectangular portion 19 adapted 25 to receive the operative connection of an operating crank-handle or rotating-means 20 therewith. Connected with said yoke-member 9 so as to be rotated thereby is a mixing element comprising a body adapted to 30 extend transversely through an opening 10 of said yoke-member. This body comprises a series of transverse interconnected loop-members 21 vertically aligned one with the other and capable of a vertical spring action 35 or spring like expansion or compression in a vertical plane. The arm 22 of the upper of said series of loop-members 21 is secured to said yoke-member 9 within its opening 10 in any suitable manner, either by 40 solder or mechanically, and being thus secured anchors the upper end of the mixing element in rigid connection with said yoke-member, and thus retains said mixing element in operative relation to said yoke-member 45 so as to be revolved thereby when said yoke-member is rotated. Connected with the lower of said series of loop-members 21 is a transversely extending scraping element comprising a series of vertically disposed and transversely aligned loop-members 50

23 providing a series of downwardly extending scraping points or fingers 24. As shown in the drawings the above described members of said mixing element are preferably formed from an integral wire rod bent in 70 proper conformation, such material providing a requisite degree of resiliency whereby the expansion and compression of the mixing element may be obtained, but it will readily be understood that so long as 75 the essential operation or function of vertical expansion and compression is retained said mixing element may be made of any other suitable material or form.

Before the can is filled with paint, the 80 mixing element is compressed to thus be moved upwardly in the opening 10 of said yoke-member 9, and thereby raise the scraping points or fingers 24 away from and space the same away from the bottom of the 85 can, and in order to retain the same compressed and under the tension of its contracted loop-members 21 a stay or block 25 of light and buoyant material, such as cork or light wood, is inserted between the mixing element and the bottom of the can. The can may be now filled with the paint and sealed by its cover member 2. As is well known ready mixed paint when left standing for any considerable time precipitates to 90 the bottom of the receptacle in which it is contained the heavier and non-soluble portion of its ingredients, thereby causing the mass in the bottom of the can to become thick and even in some cases hardened while 95 the fluid in which the ingredients were suspended becomes thin at the surface of the filled can. It is frequently very difficult, after opening a can of paint in such a condition to thoroughly mix the precipitated 100 mass with the fluid and so that the same is properly suspended in the latter, and much waste is entailed by the inability of the user to thoroughly stir up and mix the contents of the can.

Paint put up in cans constructed according to my present invention as above described, may be thoroughly mixed again and all waste eliminated by means of my novel mixing element. First the closing-member or cap 18 is removed to expose the end of the spindle member 12 so that an operating crank-handle 20 may be applied thereto, as shown in Fig. 4 of the drawings. It will be borne in mind that the compression of the mixing element maintains the scraping points or fingers raised or spaced from the bottom of the can, thus providing a space in which the sediment or precipitation of the paint ingredients settles, so that 115 the latter is normally below said scraping points or fingers. Now by turning the crank-handle 20 the yoke-member 9 is rotated and the mixing element is carried off and away from the supporting stay or block 120 125 130

25, and immediately the transverse loops 21 being freed exert their normal tension which tends to expand the mixing element and cause the scraping fingers or points 24 to move downward. The stay or block 25 becoming loosened from the bottom of the can floats up to the surface and out of the way. The tension of the mixing element causes the scraping points or fingers 24 to grind 10 upon the thick or hardened sediment or precipitation in the bottom of the can gradually loosening the same, so that as the loop-members 21 revolve, such sediment or precipitation is thoroughly agitated in the fluid content of the can until the same is properly 15 suspended therein. It will thus be apparent that not only do the loop-members 21 serve when under compression or tension to move downwardly the scraping-points toward the bottom of the can as the mixing element is revolved, but they also serve in their lateral extension when revolved in the can to provide efficient agitating means for stirring and again intermixing the loosened precipitation with the fluid content of the can. 20 After the above mixing operations have been completed, the cover-member 2 of the can-body 1, may be removed and access to the thoroughly mixed paint content of the can obtained.

I am aware that some changes may be made in the arrangements and combinations of the parts of my present invention, as well as in the details of the construction of 35 the same, without departing from the scope of this invention. Hence, I do not limit my invention to the exact arrangements and combinations of the parts as described in the foregoing specification and as illustrated in the accompanying drawings, nor 40 do I confine myself to the exact details of the construction of the said parts.

I claim:

1. In a device of the kind described, a 45 can-body, a centrally located vertically disposed rotatable yoke-member having an opening forming a longitudinal slot therein, bearings therefor, and a transverse mixing element mounted in the slot of said yoke-member so as to be revolved thereby, said mixing element being capable of compression and expansion in a vertical plane with 50 in said slot of said yoke-member.

2. In a device of the kind described, a 55 can-body, a centrally located vertically disposed rotatable yoke-member, bearings therefor, a transverse mixing element mounted in said yoke-member so as to be revolved thereby, said mixing element being capable of compression and expansion in a vertical plane, and means for retaining 60 said mixing element compressed to normally remove its lower end from the bottom of the can.

3. In a device of the kind described, a

can-body, a centrally located vertically disposed rotatable yoke-member, bearings therefor, a transverse mixing element mounted in said yoke-member so as to be revolved thereby, said mixing element being capable of compression and expansion in a vertical plane, means for retaining said mixing element compressed to normally remove its lower end from the bottom of the can, and means for rotating said yoke-member. 70

4. In a device of the kind described, a can-body, a centrally located vertically disposed rotatable yoke-member, bearings therefor, a transverse mixing element 80 mounted in said yoke-member so as to be revolved thereby, and a plurality of downwardly projecting scraping fingers connected with the lower end of said mixing element, said mixing element being capable of compression and expansion in a vertical plane. 85

5. In a device of the kind described, a can-body, a centrally located vertically disposed rotatable yoke-member, bearings therefor, a transverse mixing element mounted in said yoke-member so as to be revolved thereby, a plurality of downwardly projecting scraping fingers connected with the lower end of said mixing element, said mixing element being capable of compression and expansion in a vertical plane, and means for retaining said mixing element compressed to normally raise said scraping-fingers above 90 the can-bottom. 100

6. In a device of the kind described, a can-body, a centrally located vertically disposed rotatable yoke-member, bearings therefor, a transverse mixing element mounted in said yoke-member so as to be revolved thereby, a plurality of downwardly projecting scraping fingers connected with the lower end of said mixing element, said mixing element being capable of compression and expansion in a vertical plane, means for retaining said mixing element compressed to normally raise 110 said scraping fingers above the can-bottom, and means for rotating said yoke-member. 105

7. In a device of the kind described, a can-body, a cover-member therefor, a centrally located vertically disposed rotatable yoke-member, bearings for said yoke-member, a spindle-member connected with the upper end of said yoke-member adapted to project exteriorly through said cover-member, a transverse mixing element mounted in said yoke-member so as to be revolved thereby, a plurality of downwardly projecting scraping fingers connected with the lower end of said mixing element, and means adapted to be 120 connected with said spindle-member for rotating said yoke-member. 115

8. In a device of the kind described, a can-body, a cover-member therefor, a centrally located vertically disposed rotatable yoke- 130

- member, bearings for said yoke-member, a spindle-member connected with the upper end of said yoke-member adapted to project exteriorly through said cover-member, a 5 transverse mixing element mounted in said yoke-member so as to be revolved thereby, a plurality of downwardly projecting scraping fingers connected with the lower end of said mixing element, means adapted to be 10 connected with said spindle-member for rotating said yoke-member, and an inclosing means connected with said cover-member for normally inclosing and covering the exteriorly projecting end of said spindle-member.
- 15 9. In a device of the kind described, a can-body, a cover-member therefor, a centrally located vertically disposed rotatable yoke-member, bearings for said yoke-member, a spindle-member connected with the upper end of said yoke-member adapted to project exteriorly through said cover-member, a 20 transverse mixing element mounted in said yoke-member so as to be revolved thereby, a plurality of downwardly projecting scraping fingers connected with the lower end of said mixing element, said mixing element being capable of compression and expansion in a vertical plane, means for retaining said mixing element compressed to normally raise said scraping-fingers above the can-bottom, and means adapted to be connected with 25 30 said mixing element compressed to normally raise said scraping-fingers above the can-bottom, and means adapted to be connected with
- said spindle-member for rotating said yoke-member.
10. In a device of the kind described, a can-body, a cover-member therefor, a centrally located vertically disposed rotatable yoke-member, bearings for said yoke-member, a spindle-member connected with the upper end of said yoke-member adapted to project exteriorly through said cover-member, a transverse mixing element mounted in said yoke-member so as to be revolved thereby, a plurality of downwardly projecting scraping fingers connected with the lower end of said mixing element, said mixing element being capable of compression and expansion in a vertical plane, means for retaining said mixing element compressed to normally raise said scraping-fingers above the can-bottom, and means adapted to be connected with said spindle-member for rotating said yoke-member, and an inclosing means connected with said cover-member for normally inclosing and covering the exteriorly projecting end of said spindle-member.

In testimony, that I claim the invention set forth above I have hereunto set my hand this 11th day of December, 1914.

GEORGE P. FITZSIMMONS.
